UNITED STATES PATENT OFFICE

HEINRICH WOLLHEIM, OF BERLIN, GERMANY, ASSIGNOR TO THE AMERICAN STAMP AND TICKET VENDING MACHINE COMPANY OF WASHINGTON, DISTRICT OF COLUMBIA.

AUTOMATIC COIN-TESTER FOR COIN-FREED APPARATUS.

977,771.

Specification of Letters Patent.

Patented Dec. 6, 1910.

Application filed November 27, 1908. Serial No. 464,592.

To all whom it may concern:

Be it known that I, HEINRICH WOLLHEIM, manager, a subject of the Emperor of Germany, residing at Berlin, in the Empire of Germany, have invented certain new and useful Improvements in Automatic Coin-Testers for Coin-Freed Apparatus, of which the following is a specification.

The object of this invention is an automatic device for testing the greatness, shape, weight and material or elasticity of coins which are thrown into coin freed apparatus, preferably into such for strip-shaped material, as for example stamps or the like, tickets, bills, coupons, etc.

The essential features of the invention consist in the particular combination of the coin tester with the mechanism of the coin freed apparatus, in the especial construction of that part of the tester which tests the elasticity of the coins, further in the automatic movement of this part caused by the mechanism of the apparatus. A further peculiar feature of the invention being the combination of the means actuated by the mechanism of the apparatus, for the automatic actuating of the part for testing the elasticity, with automatic means to stop the mechanism of the apparatus on selling off.

Finally the invention relates to some improvements in the construction and arrangement of the coin tester and of the conduits for the diverse coins.

In the accompanying drawings an example of a form for carrying out the invention is illustrated.

Figure 1 is a front elevation of a part of the mechanism of the coin freed apparatus for postage-stamps or the like, with the outer casing removed, and in combination with the coin tester which is shown partly in section. Fig. 2 is a side elevation of the coin tester, partly in section, the outer casing being removed. Fig. 3 is a side elevation of a part of the selling mechanism which shows the connection between the driving mechanism for the coin tester and the means for the automatic stopping of the apparatus on selling off.

To a partition-wall 1 of the casing inclosing the whole mechanism a bracket 2 is attached upon which the mechanism for the automatic delivering of the postage-stamps or the like is supported. From this mecha-

nism the peculiar construction of which is not of importance for this invention, only some principal parts are illustrated in the drawings. It consists essentially of a casing having two side parts 3 which inclose between them the diverse means for feeding the stamp-strip 4 and to separate single cuts of it after a coin has been thrown in. The feeding mechanism for the strip consists of a pair of rollers 5, 6 arranged one beneath the other which are at best shown from Fig. 3. The front pair 5, 6 is journaled in a separate and removable part 7 of the casing 3 to enable an opening or detachment of the feeding mechanism. This feeding mechanism is operated in a known manner by the gear wheels 8 which are actuated from the main shaft 9 and which rotate the feeding rollers 5 and 6 simultaneously and in the same direction. The main shaft 9 is driven by a chain-wheel 10 and chain 11 by means of a suitable motor which is, not being an essential part of the invention, not illustrated in the drawings. The rollers 5, 6 located in the casing part 7 are automatically rotated from the rollers located in the casing 3 by the friction between them which is caused by the stamp-strip which is moved forward by the rollers in the direction indicated by the arrow. The stamp-strip is fed forward a determinate distance in known manner by the rollers 5, 6 and is separated into cuts of a determinate length. The separated strip-part falls into a delivery opening on the front side of the apparatus, the same being also not illustrated in the drawings as it is not of importance for the invention.

The coin tester consists essentially of two separated parts which the coins thrown in must pass successively. The one part 12 being arranged directly behind the introducing opening 15 located in a plate 14 fixed on the front side of the casing. This part 12 is of a construction well known and consists of two parts 16, 17 which oscillate on a common shaft 18, see Fig. 1, and form a channel 19 to let pass the coins thrown in. The channel 19 or the parts 16, 17 forming it are made at the end in an angle 20, as shown in Fig. 2, and discharge into a chute 23 arranged below them which is attached in a suitable manner, for example by a bracket 21, to a supporting plate

- 22 fixed on the partition-wall 1. This chute leads the coins discharging from the tester 12 to the second tester 13. The latter consists of a sleeve or cylinder which, as is 5 more distinctively described later on, at each operation of the selling mechanism described above by a coin thrown in is automatically rotated by a fragment of its circumference.
- 10 Each of the testers 12 and 13 has to accomplish a determinate function, *i. e.* the tester 12 the construction of which is well known serves to test the coins introduced in respect to their greatness, shape and weight, 15 that is to say it leads only such coins to the chute 23 which have the greatness, shape and weight required to actuate the apparatus in the regular manner. The second tester 13 the particular combination of which 20 with the tester 12 is an essential feature of the invention, has the function to test the coins introduced in respect to their material, this tester being so arranged and constructed that the coins discharging from the tester 25 12 at first must fall a determinate distance (through the chute 23) before it drops upon the tester 13 and are forwarded from this into a chute 24 which leads the coins to the mechanism actuating automatically by the 30 weight of the coin the driving motor of the vending apparatus. The entering slot 25 of the chute 24 is located in such a position in respect to the tester 13 that the coins dropping from the chute 23 upon the tester must 35 have a certain elasticity which causes that they rebound somewhat from the tester whereby they arrive the entering slot of the chute 24. The discharging-opening 26 of the chute 23 is in a suitable manner enlarged 40 or cut out to procure a free passage for the coin rebounded. On the other hand the chute 23 and the entering opening 25 of the chute 24 are arranged inclined to the tester in such a manner that they lie nearly in the 45 direction of the dropping and rebounding of the coins so that any dropping out of a coin into the interior of the casing of the apparatus is prevented. Thus the coin 27 thrown in, if it has the required elasticity, 50 will rebound from the bounding-piece 13, as shown in Fig. 2, and will thereby enter into the slot 25 of the chute 24 as shown in dotted lines at 27^a. On the contrary, if a coin is of bad or spurious material, it will roll down 55 from the piece 13, as shown in dotted lines at 27^b and arrive at a conduit 28 which may be so arranged that the bad or spurious coin will be returned to the customer or brought to the usual or a special receptacle for such coins 60 without having released the vending mechanism. Thus spurious coins are held back by the tester 12 and released from it at each operation of the apparatus drop directly 65 from the tester to a catch device 29 which leads back these coins directly to the de-

livery opening. The arrows in the drawings indicate the paths which the diverse coins take when passed through the testers.

The mechanism for the automatic operating of the coin testers are the following: 70 Upon the main shaft 9 of the vending mechanism is an eccentric 30 which works against a roller 31 of an oscillating lever 33 attached rigidly to a shaft 32 lying parallel to the shaft 9. The lever 33 rests against a 75 pin 34 which is fastened rigidly to an arm 35 of an angle-lever 35, 36 which oscillates upon a shaft 37 journaled in the partition-wall 1 of the casing. Upon the shaft 37 is situated a spring 38 which governs the angle 80 lever in such a manner that it always returns automatically the lever to its position of rest. Jointly connected with the lever arm 35 is further a draw-bar 39 the other end of which is jointly attached to an oscillating 85 lever 40 one end of which oscillates on a shaft 41 bearing in the plate 22. The end of the rod 39 is adjustable on the lever 40 by means of a slot 42 and screw 43, to regulate the stroke of the lever 40. At the free end 90 of the lever 40 a pawl 44 is journaled which is governed by a spring 45 attached to the lever. The pawl meshes with a ratchet-wheel 46 rigidly fastened to the bounding-piece 13 and rotating with it on a shaft 47 95 bearing in the plate 22. The other arm 36 of the angle-lever works against a pin 48 attached to the movable part 16 of the tester 12, oscillating on the journal 18.

The tester device operates as follows: 100 After one has thrown in a coin through the opening 15 and the same has passed the tester 12 and 13 in the manner described before and has come through the chute 24 to the releasing mechanism of the apparatus and thereby the driving motor, the vending mechanism comes in action during which the shaft 9 makes always one whole rotation. Thereby the eccentric 30 attached thereto 105 also rotates once wholly in the direction 110 of the arrow in Fig. 3, working against the roller 31 of the lever 33 so that the latter oscillates aside. Thus the lever moves the pin 34 of the lever arm 35 also aside so that further the angle-lever 35, 36 oscillates aside whereby its upper arm 36 works against the pin 48 of the tester 12, which pin is raised, while the other arm 35 draws forth the rod 39 connected therewith. Thereby the pawl 44 attached to the lower 115 end of the rod moves the ratchet-wheel of the tester 13 forward. Thus, after each throwing in of a coin a simultaneous action 120 of both parts of the testing device takes place, *i. e.* by lifting the pin 48 by the lever arm 36 the tester 12 is opened while the parts 16 and 17 are opened (see the position indicated by dotted lines in Fig. 1) 125 so that coins which are thrown in during the operation of the apparatus fall out from 130

the tester without further passing and are led back by the catch device 29 to the delivery opening of the apparatus. Therefore the correct operation of the apparatus 5 being not hindered by coins which are thrown in at a time at which a throwing in shall not take place. Furthermore the bounding-piece 13 is simultaneously rotated forward by the other lever arm so that each 10 coin thrown in drops upon another, fresh surface of the bounding-piece. Thereby the correct function of the latter is always insured. Simultaneously at each time an 15 automatic cleaning of the bounding-piece takes place thereby. As the drawings show beneath the bounding-piece a bow 50 is supported upon a bracket 49, the arms of the bow terminating tightly on the bounding-piece so that they slide upon them if it rotates. 20 Thereby any dirt which rests on the bounding-piece and which is mainly supplied by the coins thrown in is removed again and the bounding-piece is always kept clean. This cleaning by the scraper 50 25 takes place at each moving forward of the bounding-piece while it slides along both bow-arms. Both movements, the varying of the rebounding surface and the automatic cleaning of the bounding-piece at each 30 throwing in of a coin cause an utmost exact and sure operation of the tester. If desired, the bounding-piece may also be adjusted lengthwise to vary the bounding-surface also in the direction of its length. It is insured 35 in its position upon the shaft 47 by an adjusting screw 51.

By the acting of the lever 33 through the main-shaft 9 a further device is simultaneously operated which causes the automatic 40 stopping of the vending mechanism if the whole vending material placed in the apparatus has passed the mechanism. This device is described as follows in referring to the Figs. 1 and 3. The shaft 32 bears on its other end, opposite to the lever 33, an arm 52 the upper end of which is provided with a pin, preferably such of an angular shape. Furthermore, outside of the casing 3 of the vending mechanism upon a shaft 54 bearing in the casing 3 a weighted lever 55, 50 56 is rigidly fixed the upper arm 56 of which has at its outer end an angle-notch 57. The lower arm 55 is heavier than the upper so that it has always the tendency to oscillate 55 in the direction of the arrow of Fig. 3 and thereby to move the other lever arm 56 downward in the direction of the arrow. Rigidly fastened upon the shaft 54 is further a lever arm 58 situated inside of the 60 vending mechanism which is located between the upper rollers 5 in such a manner that it always slides against the material-strip 4 which passes through the rollers. As both lever arms 55 and 58 are rigidly 65 connected with the shaft 54 the lever arm

55 is always retained from its tendency to swing forward in the direction of the arrow, by the lever arm 58 sliding always against the strip, so that the lever arm 56 is held up in a position shown in Fig. 3 in 70 full lines.

Now if the whole of the strip-shaped material placed in the apparatus, has passed the rollers 5, 6 and the lever arm 58 finds no more a support on the strip the lever arms 75 58, 55, by the overweight of the latter, swing forward into the position shown in Fig. 3 by dotted lines. Thereby the lever arm 56 comes also in the lowered position indicated by dotted lines. At each movement of the 80 shaft 32 in the direction of the arrow Fig. 3, which movement takes place, as described before, at each throwing in of a coin, the arm 52 swings in the direction of the rotation of this shaft, i. e. in regarding Fig. 3, 85 it swings to the right into the position shown by dotted lines. The delivering of the separated strip-pieces now takes place in such a manner that every time that strip-piece is separated and delivered which lies between 90 the lower rollers 6, while simultaneously the strip-piece which was before between the upper rollers 5, leaves these rollers and enters between the lower rollers until it is delivered by a further operation of the apparatus. 95 The arrangement of levers as described is put in action now if there is the last strip-part between the upper rollers 5 and the last but one strip-part to be delivered between the lower rollers 6. In this 100 position of the strip-parts remaining in the apparatus, if a coin is thrown in, the last but one strip-part held between the rollers 6 is separated and through the rollers carried outward of the vending mechanism, to the delivery opening. At the same time the testers are operated in the manner as described before, while the shaft 32 and the lever-arm 52 connected therewith swing in the direction of the arrow in Fig. 3, and the lever-arm 52 comes into a position indicated by dotted lines. After the delivering 105 of the last but one strip-part by the rollers 6 the last strip-part enters between these rollers in leaving the rollers 5. Thereby the lever-arm 58 loses its support which it had before on the strip, so that the lever-arm 55 swings forward in the direction of the arrow and the arm 56 sinks in the direction of the arrow. By this the notch 57 of this arm 110 comes into a position before the pin of the arm 52 moves laterally so that therefore after delivering of the last but one strip-part the arm 52 is not able to go back 115 into its position of rest and thus the shaft 32 rests also in the position of action. Thus also the levers 33 and 35, 36 remain in their position of operation indicated by dotted lines in Fig. 3, so that on the one hand the tester 12 is held in the opened position 120 125 130

indicated by dotted lines in Fig. 1, and on the other hand the ratchet mechanism 39, 40, 44, 46 for the tester remains stopped. Thus, before the apparatus is filled fresh with strip-material and the lever-arm 56 is released from the pin of the arm 52 by the control-officer, a further operating of the apparatus is prevented, as the coins which may be further thrown in drop from the open tester 12 into the catch-device 29 and are therefore led back to the delivery opening of the apparatus without having any influence upon the mechanism. The essential feature of the invention in view of this arrangement is, the combination of the testers with the stopping mechanism and the common operating of all three mechanisms by only one shaft, namely by the main-shaft 9 of the mechanism. The last strip-part remaining in the apparatus may be in a condition to be used or not.

It is understood of course that the invention is not limited to the modifications of the single parts given as an example in the drawings, but regards every modification under its scope which accomplish the same or nearly the same effects.

What I claim as my invention and desire to secure by Letters Patent is,—

- 30 1. In a coin-controlled apparatus, in combination, the main shaft, a plurality of means for automatically testing the weight, size, shape and the material of the coins, and means whereby each of said plurality of means is automatically operated by the movement of said main shaft.
2. In a coin-controlled apparatus, in combination, the main shaft, means for testing the size and shape of the coins, second means for testing the material of the coins, means whereby each of said means is simultaneously and automatically operated by said main shaft, and means to lock the main shaft at a determined period.
- 45 3. In coin-controlled apparatus, a pair of independent movable coin-testers opera-

tively connected to move in substantial unison, an operating shaft intermittently actuated, and means connecting said shaft with one of the testers, the movement of the shaft 50 imparting movement to said testers.

4. In coin-controlled apparatus, a pair of testers for testing different qualities in a coin, said testers operating on a coin successively and being movable, means for 55 operatively connecting the testers to move in substantial unison, an operating shaft intermittently actuated, and means connecting said shaft with one of the testers, the movement of the shaft imparting movement 60 to both testers.

5. In a coin-controlled machine, in combination, an operating shaft, a pair of intermittently movable coin testers, and means connecting said testers with said shaft 65 whereby the latter will operate each of the testers upon its actuation.

6. In a coin-controlled apparatus, a pivoted coin tester, a chute communicating therewith, a rotatable coin tester at the base 70 of said chute, a ratchet carried by the rotatable coin tester, a pivoted arm carrying a pawl to engage with said ratchet, a rod connecting said arm with said first coin tester, an operating shaft, and means 75 whereby said shaft when actuated will move said pivoted coin tester and thereby actuate said rod to cause said rotatable coin tester to partially rotate.

7. In a coin-controlled apparatus, a pair 80 of intermittently movable spaced-apart coin testers, and means whereby the movement of one will be communicated to and operate the other.

In testimony whereof I have set hereunto 85 my signature in the presence of two witnesses.

HEINRICH WOLLHEIM.
